UNITED STATES PATENT OFFICE.

PAUL MAUSER, OF OBERNDORF-ON-THE-NECKAR, GERMANY.

EJECTOR DEVICE FOR AUTOMATIC FIREARMS.

1,035,210.

Specification of Letters Patent. Patented Aug. 13, 1912.

Application filed March 28, 1912. Serial No. 686,852.

To all whom it may concern:

Be it known that I, PAUL MAUSER, privy councilor, a subject of the King of Wurttemberg, residing at Oberndorf-on-the-Neckar, in the Kingdom of Wurttemberg, Germany, have invented certain new and useful Improvements in Ejector Devices for Automatic Firearms, of which the following is a full, clear, and exact description.

10 The invention relates to an ejector for automatic firearms which consists of an ejector rod longitudinally slideable on the breech closure and a resilient ejector lever acting with a yielding tappet on the ejector rod. In 15 accordance with the invention the tappet is pivoted as a separate pawl on the spring-controlled ejector lever and after the ejection it is rocked outward by the ejector rod acting on a nose on this pawl, whereby 20 owing to the bearing of a second nose on the pawl on the lower face of the wall of the frame, the ejector lever is simultaneously 25 pressed downward.

An embodiment of the invention is illustrated in the accompanying drawing in which:

Figure 1 shows the rear part of the firearm in partial longitudinal section. Fig. 2 is a corresponding section with the breech closure in its rear end position. Fig. 3 shows the breech closure in longitudinal section partly in elevation with the ejector rod occupying its normal position. Figs. 4 and 5 show the tappet in plan and side elevation.

35 The ejector rod u has a limited displacement on the under side of the breech closure k and at its front end carries an impact shoulder u^1 rising from rear to front and which is able to pass outward over the head 40 of the breech closure through a suitable recess therein. The ejector rod is rendered operative by a nose w^3 on the rear arm w^1 of the pawl w which is rotatable about a pin w^0 and its front arm w^2 carries at its upper 45 part a rounded nose w^4 . The pin w^0 is mounted on the rear arm w^1 of the ejector lever w which is suspended rotatably on the pin w^0 in a lower recess in the lock casing

its rear arm being constantly pressed upward by the helical spring x^3 embedded in 50 the front arm w^2 . When the breech closure k springs back after firing the ejector rod which occupies its normal position (Fig. 3) 55 encounters the nose w^3 by which it is pressed forward (Fig. 1) whereby the empty cartridge case is ejected. As soon as the ejector rod has reached its front end position, upon the further recoil of the breech closure the rear end of this rod presses against the 60 chamfered front face of the nose w^4 so that the latter yields in a downward direction 65 whereby the rear lever arm w^1 is rotated downwardly. As, however, the nose w^4 on the front lever arm w^2 bears on the lower 70 face of the wall of the frame this rotation simultaneously produces the depression of the rear lever arm w^1 in opposition to the action of the spring x^3 . In this manner the tappet is depressed to such an extent that the ejector rod is able to pass over it. The 75 rotation of the lever w on the lever x is confined within the necessary limits by means of stops.

When I claim as my invention and desire to secure by Letters Patent is:

An ejector device for automatic firearms, comprising a breech closure, an ejector rod longitudinally slideable thereon, a frame, an ejector lever, spring means for controlling said lever, a yielding tappet in the form of 80 a separate pawl, provided with a plurality of noses and pivoted to the ejector lever to enable the latter to act on the ejector rod, the said pawl, after the act of ejection, being adapted, by the engagement of the ejector rod with a nose of the pawl, to be rocked outwardly whereby, owing to the engagement of the other nose of the pawl on the lower face of the said frame, the ejector lever is simultaneously depressed.

In testimony whereof I have affixed my signature in presence of two witnesses,

PAUL MAUSER.
